(57) **CLAIM**

The ornamental design for an air humidifier, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a perspective view of first embodiment of an air humidifier showing my new design;

FIG. 1.2 is a front view thereof;

FIG. 1.3 is a back view thereof;

FIG. 1.4 is a left side view thereof;

FIG. 1.5 is a right side view thereof;

FIG. 1.6 is atop plan view thereof;

FIG. 1.7 is a bottom plan view thereof;

FIG. 2.1 is a perspective view of second embodiment of an air humidifier showing my new design;

FIG. 2.2 is a front view thereof;

FIG. 2.3 is a back view thereof;

(Continued)

FIG. 2.4 is a left side view thereof;
FIG. 2.5 is a right side view thereof;
FIG. 2.6 is a top plan view thereof;
FIG. 2.7 is a bottom plan view thereof;
FIG. 3.1 is a perspective view of third embodiment of an air humidifier showing my new design;
FIG. 3.2 is a front view thereof;
FIG. 3.3 is a back view thereof;
FIG. 3.4 is a left side view thereof;
FIG. 3.5 is a right side view thereof;
FIG. 3.6 is a top plan view thereof; and
FIG. 3.7 is a bottom plan view thereof.
